UNITED STATES PATENT OFFICE.

GEORGE ARTHUR BIDDELL, OF IPSWICH, ENGLAND, ASSIGNOR TO GEORGE BOWER, OF FAYETTE, MISSOURI.

FITTINGS OF FURNITURE-DRAWERS.

SPECIFICATION forming part of Letters Patent No. 437,556, dated September 30, 1890.

Application filed May 3, 1889. Serial No. 309,461. (No model.) Patented in England April 3, 1877, No. 1,298.

To all whom it may concern:

Be it known that I, GEORGE ARTHUR BIDDELL, of Ipswich, in the county of Suffolk, England, have invented a new and useful Improvement in the Fittings of Drawers and other like Articles of Furniture, (for which I have received Letters Patent in Great Britain, dated April 3, 1877, No. 1,298,) of which the following is a specification.

5 The invention consists in the construction described, and pointed out in the claim.

In order that my invention may be fully understood, I will now describe the same with reference to the accompanying drawings, in which—

10 Figure I is a central vertical section through a chest of drawers, and Fig. II is a section on line *y y* through the chest.

15 A is the casing, and B the drawers. The roller C is fixed below each drawer near the front end of the chest, and is adapted to revolve in two apertures made in the bearing-pieces *f*. One end of each cord D is carried through holes at the back of the drawer, as

20 at *g*, and secured by a knot. The cords are wrapped two or more times around the roller and the other ends carried around screws *s*, firmly fixed in the bottom edge of the front of the drawer, and made fast to cleats *h*, attached to the under side of the bottom of the

25 drawer.

In this device the cords are not exposed across the drawer when it is pulled out, and so are not in the way in getting articles in and out of the drawer, and besides there is 35 not so much danger of the articles being caught by the roller.

The combination of a drawer and its casing, a roller supported by one of said parts, and a flexible guide engaging the periphery of 40 the roller and secured at its ends to the other of said parts being old,

I claim herein—

The combination, with a drawer and its casing, of a shaft or roller suitably journaled in 45 the casing near the front of the bottom of the drawer and at right angles to the line of movement, cords or equivalent flexible connections, one near each end of and secured to the drawer in rear of the roller and wound around 50 the roller, projections on the under side of the drawer, around which the free ends are carried, and cleats to which the free ends are made fast, substantially as set forth.

GEORGE ARTHUR BIDDELL.
